UNITED STATES PATENT OFFICE.

ABRAHAM B. KOPLIN, OF HELLERTOWN, PENNSYLVANIA, ASSIGNOR OF ONE-HALF TO AARON HOSTETTER, OF HANOVER, PENNSYLVANIA.

STAIR-CARPET FASTENER.

SPECIFICATION forming part of Letters Patent No. 557,586, dated April 7, 1896.

Application filed July 19, 1895. Serial No. 556,535. (No model.)

To all whom it may concern:

Be it known that I, ABRAHAM B. KOPLIN, a citizen of the United States, residing at Hellertown, in the county of Northampton and 5 State of Pennsylvania, have invented a new and useful Stair-Carpet Fastener, of which the following is a specification.

This invention relates to an improvement in stair-carpet fasteners, and is designed to 10 be used either independently of or in connection with a stair-rod for holding a stair-carpet snugly in place.

The object of the present invention is to 15 provide a simple, inexpensive, and efficient fastening device for stair-carpets which may be manipulated with ease, which may be used either with or without rods for holding the carpet in place, which will not injure the carpet, which may be clamped firmly in position 20 without the aid of screws, and which may be moved with facility when required.

In order to accomplish the objects above 25 enumerated, the invention consists in a stair-carpet fastener embodying certain novel features and details of construction whereby advantages in point of simplicity, ease of manipulation, and efficiency are attained, as hereinafter fully described, illustrated in the drawings, and finally embodied in the claims.

30 In the accompanying drawings, Figure 1 is a detail perspective view of an improved stair-carpet fastener constructed in accordance with this invention. Fig. 2 is an end elevation of the same. Fig. 3 is a perspective

35 view illustrating the manner in which the improved fastening device is applied in practice, showing the same used independently and also in connection with a stair-rod.

Similar numerals of reference designate 40 responding parts in the several figures of the drawings.

Referring to the accompanying drawings, the improved stair-carpet fastener contemplated in this invention is preferably formed 45 from cast metal, although it will be apparent from the ensuing description that the same may be stamped or otherwise formed from sheet metal if desired.

The fastener is substantially L-shaped in 50 cross-section, being formed with a vertical portion or main body 1 and with a horizontal

base or forwardly-extending portion 2 formed integrally therewith. The forward face of the vertical or upright portion 1, as well as the upper face of the horizontal base portion 55 2, may be formed or have represented thereon any desired ornamental design, and the rear face of the vertical or upright portion may or may not be provided with a recess 3, adapted, when the fastener is secured in place, to 60 receive the end of a stair-rod of any ordinary description.

4 designates a pointed barb or prong, which is preferably formed integrally with the fastener, the same being arranged at the inner 65 end of the horizontal base portion and beneath the vertical or upright portion and extending downwardly, adapting it to engage and penetrate the carpet and the tread portion of a step. The vertical or upright portion 1 is formed at 70 or near its upper end with a perforation 5, through which a nail may be driven into a stair-riser for preventing upward movement of the fastener. This perforation is partially surrounded upon the front face of the vertical or upright portion 1 by two substantially 75 semicircular ribs or projections 6, which, when the nail referred to is driven through said perforation, receive the head thereof and limit its inward progress. Sufficient space is 80 left between said ribs or projections for enabling an instrument or tool, such as a pair of pliers, to pass between the same for engaging the head of the nail and withdrawing the latter. 85

In operation the improved fastener described is pressed against the stair-carpet overlying the riser, and while it is pressed firmly inward it is at the same time thrust downward, the horizontal base portion thereof 90 being struck by a hammer for causing the prong or barb 4 to pass through the carpet and penetrate the tread of the step, a nail being thereafter driven through the perforation 5, in the manner described above, for holding the fastening device against upward 95 displacement. Two of these fasteners are preferably employed for each step, one at or near the opposite side edges of the strip of carpet. 100

If so desired, a stair-rod of any preferred description, such as is indicated at 7, may be

used in connection with a pair of these fasteners, the ends of said rod being passed behind the vertical portions thereof and into the recesses 3 above described.

5 From the foregoing description it will be seen that a very simple, inexpensive, and efficient stair-carpet fastener is obtained, which may be secured in place without the use of screws, which may be used independently of 10 or in connection with stair-rods, which may be quickly applied, and which may be removed with equal facility.

Having thus described the invention, what is claimed as new, and desired to be secured by 15 Letters Patent, is—

1. A carpet-fastening device, comprising a body portion having a perforation for the securing device, a divided rib or flange partially surrounding said perforation for facilitating 20 the extraction of the securing device, a base portion substantially at right angles to the body portion, and a depending barb project-

ing from the base portion, substantially as and for the purpose described.

2. A carpet-fastening device comprising a 25 vertical or upright portion formed with a perforation for the reception of a securing device, a forwardly-projecting divided rib or flange partially surrounding said perforation and facilitating the extraction of the securing device, a horizontally-extending base portion projecting substantially at right angles to the upright portion, and a pointed barb or prong disposed beneath and projecting downwardly from said base portion and in alignment with the vertical portion, substantially as and for the purpose set forth.

In testimony that I claim the foregoing as my own I have hereto affixed my signature in the presence of two witnesses.

A. B. KOPLIN.
